UNITED STATES PATENT OFFICE.

W. H. NICHOLS, OF EAST HAMPTON, CONNECTICUT, ASSIGNOR TO A. H. MARKHAM, W. H. NICHOLS, AND DAVID STRONG, OF SAME PLACE.

COFFIN-SCREW.

Specification of Letters Patent No. 24,911, dated July 26, 1859.

To all whom it may concern:

Be it known that I, W. H. NICHOLS, of 5
East Hampton, in the county of Middlesex
and State of Connecticut, have invented a
new and Improved Coffin-Screw; and I do
hereby declare that the following is a full,
clear, and exact description of the same, reference
being had to the accompanying drawings,
forming a part of this specification, in
10 which—

Figure 1 represents a vertical central section
of my invention as applied to a real
screw. Fig. 2 is a similar section of my
invention as applied to a tack or imitation
screw. Fig. 3 is a plan or top view of the
15 plate which I use to retain the cap or cover
of the screw. Fig. 4 is a similar view of the
cap.

Similar letters of reference in all the figures
20 indicate corresponding parts.

Coffin screws are divided into two distinct
classes; one class comprising real
screws, intended to fasten two parts of the
coffin together; and the other comprising
25 imitation screws, that serve only for ornament,
and which usually consist of tacks with
their heads covered like the screws.
My invention applies to both these classes,
and it consists in a peculiar method of
30 securing the cap or cover of the head of the
screws or tacks after the latter have been
inserted by passing said screws or tacks
through round plates, the edges of which
are beveled off, or screwed, so that the caps
35 can be driven on by a light blow, or screwed
on after the screws, or tacks have been
driven in to their full length, and that the
outward appearance of the caps is not injured
and kept perfectly intact.

40 To enable those skilled in the art to make
and use my invention I will proceed to de-
scribe it.

Instead of securing the caps, or covers directly
45 to the heads of the screws or tacks, which proceeding rendered them very liable
to come off as the screws are inserted or to
become injured when the tacks are driven in,
I use plates, A, having holes, a, in their
centers so that the screws, b, or tacks, c,

50 pass freely through them and that by means
of the screws, or tacks themselves these
plates can be secured to the required spot.
The edges of these plates are beveled off, as
shown in Fig. 2, when the same are used for
55 tacks or imitation screws, and the caps, B,
are driven on by a light blow after the
tacks are inserted. When used for real
screws, as represented in Fig. 1, the edges
of these plates are screwed so that the caps
60 can be secured to them by means of a screw-
thread cut into their inside and that they
(the caps) can be removed at pleasure.
This is necessary because the screws, b, or
some of them have to be taken out and put
65 in several times, whereas the tacks, c, or the
imitation screws when once inserted are
never disturbed.

The caps, B, are “spun” of sheet brass
and plated if desired, or they may be made
of German silver or of any other suitable
70 material, all of the same size and so that
they fit nicely to the plates, A, which latter
are cast and need no finish or additional
labor, with the exception of those serving
75 to retain the caps of the screws, in which
case it is necessary to put the plates in a
lathe and cut the screw thread on their
edges.

By these means the covers or heads for
coffin screws can be made cheaper and more
80 permanent than by fastening the covering
directly to the heads of the screws, or tacks
and the screws can be taken out and put in,
as many times as may be desired, without
85 injury to the appearance of the caps or
covers.

Having thus fully described my invention
what I claim as new, and desire to secure
90 by Letters Patent, is:—

The employment of plates, A, or their
equivalent, for the purpose of securing or
retaining the caps or covers, B, of coffin
screws or tacks, substantially as herein set
forth.

W. H. NICHOLS.
